UNITED STATES PATENT OFFICE.

SIGMOND SCHREIBER, OF PITTSBURGH, PENNSYLVANIA.

DESIGN FOR A DISPENSING SUGAR BOWL.

Application filed April 13, 1925. Serial No. 13,112. Term of patent 7 years.

To all whom it may concern:

Be it known that I, SIGMOND SCHREIBER, a citizen of the United States of America, residing at Pittsburgh, in the county of Allegheny and State of Pennsylvania, have invented a new, original, and ornamental Design for a Dispensing Sugar Bowl, of which the following is a specification, reference being had to the accompanying drawing, forming a part hereof.

In the drawing:

Fig. 2 is a horizontal section on the line 2—2 of Fig. 1, and

Fig. 3 is an elevation at a right angle to Fig. 1.

I claim:

The ornamental design for a dispensing sugar bowl, as shown.

SIGMOND SCHREIBER. [L. S.]
